UNITED STATES PATENT OFFICE.

HARRY AYLiffe, OF LONDON, ENGLAND, ASSIGNOR TO CARIBONUM LIMITED, OF LEYTON, ESSEX, ENGLAND.

METHOD OF ATTACHING LABELS OR THE LIKE.

No Drawing.

Application filed September 27, 1923. Serial No. 665,239.

To all whom it may concern:

Be it known that I, HARRY AYLiffe, subject of the King of Great Britain, residing at 90 Woodside Green, London, S. E. 25, 5 England, have invented certain new and useful Improvements in Methods of Attaching Labels or the like, of which the following is a specification.

This invention relates to methods of attaching a label for ornamentation or otherwise to a surface, and particularly refers to the labelling of boxes formed from sheet metal, for instance, inking pad receptacles.

The main object of the present invention 15 is to obtain a means of fixing a label so that an artistic result obtains.

Another object is to provide a fixing means for labels which is of lasting character.

20 Another object is to obtain a method of fixing which results in the label being protected from the atmosphere, and a particular object is to provide a means of fixing a label to an ink pad or like tin having all the advantages stated above, and which is further protected against accidental removal.

According to the present invention, a sheet duly ornamented or printed on is attached to the required surface by carrying 30 out the following steps:—

Coating the surface with a varnish, smearing the sheet with a softening agent for celluloid, pressing a film of celluloid over the smeared sheet, further pressing the 35 celluloid-covered sheet with the application of heat, and finally pressing the sheet so treated on to the surface, the said final pressing operation being accompanied by the application of heat.

40 The pressing of the sheet and celluloid film may be effected by heated rollers of the ordinary character found in printing establishments, and the softening agent—which may be methylated spirit—having slightly 45 softened the under-surface of the celluloid film, the pressure under heat causes absolute adherence of the sheet and the film so that they are inseparable.

The attachment of the label so formed 50 to the surface where it is wanted may be achieved by applying heat if the said surface is already coated with a varnish, as is usually the case when dealing with coloured tins, or by applying a thin layer of varnish 55 directly on the said surface or over a colour

layer applied thereto where not already of such a character as to be affected by heat. The heat may be applied in either case by means of a stamp press with a heated die, it being important that the heat shall not 60 be so high in temperature as to reduce the polish of the celluloid film. The methylated cardboard or paper surface to which printing has been applied is placed with the varnish surface under the heated die of a 65 stamp press and pressed over two or three seconds, upon which complete adherence to the said surface is achieved.

The surface to which the label is to be attached is preferably larger than the label, 70 and in the case of a tin box particularly for stamp pads, the pressing die is formed so that the process results in causing a slight depression or recess in the surface of the lid which has to be occupied by the celluloid 75 and paper label. By careful attention to detail a very artistic and useful result is obtainable, which is substantially permanent in practice, since the edges of the label are protected by the border to the recess against 80 the possibility of being raised at the corners, as is the case with a label pressed on a flat surface.

In the particular case of the box for a stamp pad, the base colour of the tin is applied by a machine which finishes the same off, either with an admixture of varnish and the colour, or by a second coat of varnish applied on the colour layer. In either case, the said surface can be made thoroughly adhesive by means of heat coming 85 from the hot die, and perfect adherence is 90 obtained thereby.

I claim:—

1. Method of attaching a sheet to a surface, consisting in coating the surface with varnish, smearing the sheet with a softening agent for celluloid, pressing a film of celluloid over the smeared sheet, further pressing the celluloid-covered sheet with the application of heat, and finally pressing the sheet so treated on to the surface, the said final pressing operation being accompanied by the application of heat. 95

2. Method of attaching a sheet to a surface, consisting in coating the surface with varnish, smearing the sheet with a methylated spirit, pressing a film of celluloid over the smeared sheet, further pressing the celluloid-covered sheet with the application of 100 105 110

heat, and finally pressing the sheet so treated on to the surface, the said final pressing operation being accompanied by the application of heat.

3. Method of attaching a sheet to a surface larger than the sheet, consisting in coating the surface with varnish, smearing the sheet with a softening agent for celluloid, pressing a film of celluloid over the 10 smeared sheet, further pressing the celluloid-covered sheet with the application of heat, and finally pressing the sheet so treated on the said surface so that the surface is recessed, the sheet becoming protected by 15 the bordering face of the said surface, the said final pressing operation being accompanied by the application of heat.

4. Method of attaching a paper label to a surface formed from sheet tin larger than 20 the label, consisting in applying to the surface a colour layer and a varnish, smearing the label with a softening agent for celluloid, pressing a film of celluloid over the

smeared sheet, further pressing the celluloid-covered sheet with the application of 25 heat, and finally pressing the label so treated on to the surface, the said final pressing operation being accompanied by the application of heat.

5. Method of attaching a paper label to a 30 surface formed from sheet tin larger than the label, consisting in applying to the surface a colour layer and a varnish, smearing the label with a softening agent for celluloid, pressing a film of celluloid over the 35 smeared label, further pressing the celluloid-covered label with the application of heat, and finally pressing the label so treated on the said surface so that the surface is recessed, the label becoming protected by the 40 bordering face of the said surface, the said final pressing operation being accompanied by the application of heat.

In testimony whereof I affix my signature.

HARRY AYLiffe.
